TIE TETHER

Herman Cohn, Baltimore, Md.

Application May 14, 1935, Serial No. 21,428

6 Claims. (Cl. 24—49)

This invention relates to tie tethers and has for its object the provision of a necktie holder which while keeping the tie in place allows it a range of free lateral movement.

5 Tie holders as known up to the present time, function by rigidly gripping the shirt and holding the tie in an inflexible mechanical manner which is objectionable from the standpoint of good taste.

The tie tether constituting the present invention permits the tie to drape itself freely and naturally with respect to the shirt, responsive to the various movements of the body within the limits of its range of unrestraint, but prevents it from being blown over the shoulder or hanging 15 away from the body when the wearer bends forward.

Among the more specific objects of the invention are to provide a tie tether swingable relative to a button or button hole of a shirt; to provide a tie tether swingable from a clamp; to construct a tie holder laterally slidable relative to a shirt-engaging member; to provide a tie holder in which the tie-embracing member may be either rigid or flexible, and in the case of the latter type, 25 to construct the laterally movable member in the form of a spreader so that the flexible element will not constrict the edge portions of the necktie.

Other objects of the invention will appear as 30 the following description of a preferred and practical embodiment thereof proceeds.

In the drawing which accompanies and forms a part of the following specification and throughout the several figures of which the same characters of reference have been employed to designate identical parts:

Figure 1 is a perspective view of a figure with the necktie tether of my invention functioning with respect to a necktie;

40 Figure 2 is a perspective view of the necktie tether shown in Figure 1 in which a plain hook engages the button hole;

Figure 3 is a modified form in which a T-bar affords the means of attachment to the shirt;

45 Figure 4 is a perspective view of a modified form of the invention in which a clamp forms the means of shirt attachment;

Figure 5 is a further modification illustrated 50 in perspective comprising a triangular skeletal spreader;

Figure 6 is a view similar to Figure 5 excepting that the spreader is triangular;

55 Figure 7 is a perspective view of another specific embodiment of the invention in which the move-

ment of the tether is limited to rectilinear sliding movement; and

Figure 8 is a perspective view of still another form of the invention;

Referring now in detail to the several figures, 5 and first to that form of the invention shown in Figures 1 and 2, the numeral 1 represents in general a rigid wishbone shaped frame functioning both as a spreader for the flexible chain 2 and as a suspending means for the device. It includes 10 a hook 3 adapted to be inserted in the button hole of the shirt so that the tie tether can swing freely to the right or left. The tie is designed to be inserted as is indicated in Figure 1, in front of the frame 1 and behind the chain 2, the latter 15 alone showing at the front of the tie. It will be understood from the above construction that the tie is free to swing sideways through a limited range, but cannot blow over the shoulders or swing to any extreme distance away from the 20 body when the wearer bends forward. The spreader assures that the weight of the chain shall be taken off the edges of the tie and prevents the tie from being drawn and constricted by the 25 chain.

In Figure 3, the spreader 4 is formed of two wires 5 and 6 diverging downwardly and at their upper ends brought into a position of parallelism as indicated at 7 and having their extreme ends bent rectilinearly outwardly to form the T-bar 8. 30 The parallel portions of the wire are soldered or brazed together or otherwise caused permanently to units. The tie holder is inserted in the button hole preferably by turning it sideways so that the T-bar is parallel to the length of the button 35 hole. Then when the tie holder is in its normal position the T-bar 8 is transverse to the slit of the button hole and cannot come out.

Figure 8 illustrates another form of invention 40 which is adapted to be hooked into the button hole by means of the hook 9. This hook has an eye 10 receiving the bent spreader 11 which passes freely through the eye. In this form of the invention the tie-restraining element could be either flexible or rigid, but is here indicated 45 as a rigid bar 12 embossed to represent a rope. The nature of the embossing of course has nothing to do with the invention. This tie tether not only has the capacity to swing from the button hole by means of the hook 9, but it also 50 has a swivel movement produced by the connection spreader 11 with the eye 10 in the hook 9.

In those forms of the invention which have thus far been described, it is necessary that the tie tether be placed at a definite point relative 55

to the necktie due to the fact that it must be secured within the button hole of the shirt. This might not always be the optimum point at which it is desired to have the tie tether. Consequently, those forms of the invention illustrated in Figures 4, 5, 6, and 7 have been devised in which a rigid clamp 13 has been employed engageable with the edge of the front hem of the shirt. In Figure 4 the tie tether comprises a wishbone shaped spreader 14 similar to that shown in Figure 2, and from which is suspended the flexible element 2. The spreader 14 has an eye 15 linked to the clamp 13 by means of a ring 16.

Figure 5 shows the same clamp 13 and suspended from it is a frame or spreader of triangular form comprising the side bars 17 and 18 and the cross bar 19. The chain 2 is suspended at the ends of the cross bar. The necktie is designed to overlie the clamp 13 and the triangular frame and to be inserted within the closed loop 20 between the frame and the chain.

Figure 6 shows a form of the invention which distinguishes from Figure 5 solely in that the triangular frame consisting of the bars 17, 18, and 19 is substituted by a solid triangular spreader 21 made of substantial sheet material and from the lower angles the chain 2 is suspended. The triangular spreader is suspended from the clamp by means of the ring 17.

In those forms of the invention which have been described, the permissible motion of the tie tether and the necktie restrained therein has been one of oscillation about a pivotal axis which in certain instances was the button hole and in other instances the point of connection of the spreader with the shirt-engaging clamp.

Figure 8 illustrates a form of the invention in which the lateral movement of the tie tether in either direction is limited to a rectilinear path. With this end in view, the clamp 13 is provided with a loop 22, the cross member 23 of which forms a track or guide which in the illustrated embodiment of the invention is parallel to the lower edge of the clamp 13. The movable member of the tie tether is a triangular loop 24 having a sleeve 25 at its upper end slideable along the track 23. The loop 24 is adapted to receive the necktie, the permitted movement of which is lateral in either direction the same as with all the other forms of the invention.

In any of the illustrated examples of the invention in which a clamp is employed as the shirt-engaging member, the clamp may be equipped with a sliding detent 26 suitably retained within a frame 27, the sides of the latter forming a guide along which the detent slides. The detent lacks resilient contact with the shirt and its object is to let the shirt get some distance within the clamp by pushing against the detent before it enters into clamping relation with the detent. This permits the clamp to be positioned

to its full depth along the hem of the shirt while at the same time minimizing the length of the path of frictional contact between the clamp and shirt, saving wear upon the shirt and facilitating the positioning of the clamp.

While I have in the above description disclosed what I believe to be a number of practical embodiments of my invention, it will be understood that the details of constructions as shown and described are merely by way of example and not to be construed as limiting the scope of the invention as claimed.

What I claim is:

1. Tie tether comprising a spreader having divergent sides and a tie-restraining member secured at its ends to the sides of said spreader forming therewith a loop for receiving a necktie, said spreader being mounted for lateral movement to afford a range of lateral movement for a necktie, and means for attaching said spreader to a shirt.

2. Tie tether comprising a spreader having divergent sides and a flexible tie-restraining member secured at its ends to the sides of said spreader, forming therewith a loop for receiving a necktie, said spreader being mounted for lateral movement to afford a range of lateral movement for a necktie, and means for attaching said spreader to a shirt.

3. Tie tether comprising a triangular spreader having divergent sides and a tie-restraining member secured at its ends to the sides of said spreader forming therewith a loop for receiving a necktie, said spreader being mounted for lateral movement to afford a range of lateral movement for a necktie, and means for attaching said spreader to a shirt.

4. Tie tether comprising a triangular spreader having divergent sides and a flexible tie-restraining member secured at its ends to the sides of said spreader and depending therefrom, forming therewith a loop for securing a necktie, said spreader being mounted for lateral movement to afford a range of lateral movement for a necktie, and means for attaching said spreader to a shirt.

5. Tie tether comprising a spreader having divergent sides and a tie-restraining member secured at its ends to the sides of said spreader forming therewith a loop for receiving a necktie, and a shirt-engaging clamp suspending said spreader with freedom of lateral movement to afford a range of lateral movement for a necktie.

6. Tie tether comprising shirt-engaging means including an eye and an angularly bent rigid spreader freely passing through said eye, and a tie-restraining member bridging the ends of said spreader forming therewith a loop for receiving a necktie and shiftable laterally with respect to said shirt-attaching means.

HERMAN COHN.
